UNITED STATES PATENT OFFICE

HENRY E. BARROLL, OF CHICAGO, ILLINOIS, ASSIGNOR TO HENRY BARROLL & CO. INC.,
OF CHICAGO, ILLINOIS, A CORPORATION OF NEW YORK

CONTAINER

Application filed December 16, 1927. Serial No. 240,363.

My invention relates to a container, dispensing container or the like, and has for particular purpose the provision of means for permitting the ready pouring of the contents of such a container. One object is the provision of a rocking support for such a container, whereby it may easily and controllably be tilted into pouring position. Another object is the provision of such a support, which will 10 space the bottom of the container above the surface upon which it is positioned. Another object is the provision of a rocking support for a container which shall be normally positioned in close contact with the container, 15 when the container is in position, but which may be readily moved or tilted into pouring position.

Other objects will appear from time to time in the course of the specification and claims.

20 I illustrate my invention more or less diagrammatically in the accompanying drawings, wherein—

Figure 1 is a side elevation of one form of my invention with the support in position for 25 shipment;

Figure 2 is a side elevation showing my container with the rocking support in operative position, and illustrating the use of such support;

30 Figure 3 is a section along the line 3—3 of Figure 2;

Figure 4 is a detail;

Figure 5 is a further variation, as applied to a rectangular container; and

35 Figure 6 is a further variation, as applied to a crate about the container.

Like parts are indicated by like symbols throughout the specification and drawings.

Referring to Figures 1 to 4 A indicates any 40 suitable container herein shown as a cylinder or drum having the top A¹, bottom A² and the pouring opening or spout A³.

B indicates a band about the lower portion of the container which is shown as having the 45 outwardly projecting loops or elbows B¹ to one side of which is pivoted, as at B² the rocking member generally indicated as B³ and including generally horizontal sections B⁴ adapted to underlie and support the can bottom, the rocking sections proper B⁵, project-

ing forwardly therefrom and the re-curved connecting portion B⁶, which may contact the front of the container.

Referring to Figure 2 the full line position illustrates the container at rest and the dotted line position illustrates the container as tilted to pouring position.

Referring to the form of Figure 5 I illustrate a rectangular container C about the bottom of which is shown a band C¹ to opposite sides of which are pivoted the rocking members C². Each such member has a horizontal supporting surface C³, shown as positioned in a plane beneath the plane of the bottom of the container. In order to connect the two members C², and to limit their rotation, so that they will take the position shown in Figure 5, I provide a cross member or brace C⁴ which, when the device is in pouring or dispensing position, engages the front of the container. C⁵ indicates the forward and upwardly projecting rocking surfaces. When the container is to be shipped the device is swung into the position shown in dotted line in Figure 5, the parts being so proportioned and positioned that there is a minimum of projection outwardly from the container.

It will be realized that I do not wish to be limited to the direct application of my rocking support to the container itself, since it 50 may be applied to a housing or crate or frame work about such a container. I illustrate such an application in Figure 6 wherein about the container C I show a frame work or crate including the vertical corner members D the top transverse members D¹ and the bottom transverse members D². Pivoted at opposite sides to the members D² is a rocking support generally indicated as D³, which 55 includes the horizontal supporting portions D⁴, the rocking portions proper D⁵ and the transverse connecting portion D⁶. The rocking portions may seat in notches D⁸ in the bottom transverse frame member D⁹. D¹⁰ is any suitable cross member or abutment 60 for the portion D⁶.

It will be realized that whereas I have described and shown a practical and operative device nevertheless many changes might be made in size, shape, number and disposition 100

of parts without departing from the spirit of my invention. I therefore wish my drawings and description to be taken as in a broad sense illustrative and diagrammatic rather than as limiting me to my specific showing.

5 In particular I wish it to be understood that my claims, unless specifically worded to the contrary, shall be intended to cover the application of my device to a crate or housing or outer supporting or intermediate members applied to the exterior of or surrounding a container. In practice in most cases I prefer to apply the rocking support direct to a container, but under many circumstances it is desirable as shown in Figure 6, to apply it to a framework or crate.

A further advantage of my device is the provision, when the container is supported upon my rocking support, of an area of support falling substantially within the periphery of the container, whereby tilting of the container is made easier and if such area of support were coextensive with the bottom of the container. The support is, however, so proportioned as to throw the center of mass at all times to the rear of the point of support, after the container is tilted, so that it will automatically return to non-pouring position if released.

30 I claim:

1. The combination with a container of a rocking supporting member pivoted thereto adjacent the face of said container base or ground-engaging portion thereof, said member being normally positioned, at one limit of its arc of rotation, against the side of the container, and being positioned, at the opposite limit of its rotation, in rocking position beneath the container between its base and the ground, said support being adapted to underlie and support the container when the container is in normally upright position.

2. The combination with a container of a rocking supporting member pivoted thereto adjacent the face of said container, said member being normally positioned, at one limit of its arc of rotation, against the side of the container, and being positioned, at the opposite limit of its rotation, in rocking position beneath the container, the rocking member when in such rocking position extending from beneath said container upwardly and outwardly beyond the peripheral confines of the container.

3. The combination with a container of a rocking support in pivotal relation with said container, said support being pivoted adjacent the bottom of said container and being adapted, at one limit of its rotation, closely to engage the sides of said container above the bottom, and being adapted, at another limit of its rotation, to extend beneath and outwardly from said container.

4. The combination with a container of a rocking support in pivotal relation with said

70 container, said support being pivoted adjacent the bottom of said container and being adapted, at one limit of its rotation, closely to engage the sides of said container, and being adapted, at another limit of its rotation, to extend beneath and outwardly from said container, said rocking support including a plurality of generally horizontal supporting sections pivoted near their respective ends at opposite sides of said container, and extending from their pivotal connections beneath the level of the bottom of said container, and rocking portions upwardly and outwardly projecting therefrom.

75 5. The combination with a container of a rocking support in pivotal relation with said container, said support being pivoted adjacent the bottom of said container and being adapted, at one limit of its rotation, closely to engage the sides of said container, and being adapted, at another limit of its rotation, to extend beneath and outwardly from said container, said rocking support including a plurality of generally horizontal supporting sections pivoted near their respective 80 ends at opposite sides of said container, and extending from their pivotal connections beneath the level of the bottom of said container, rocking portions upwardly and outwardly projecting from the horizontal supporting sections, and a transverse member connecting said rocking portions and adapted to contact said container intermediate its top and bottom.

85 6. The combination, with a container, of a rocking support therefor of substantially U-shape, the legs of which straddle the container and are pivotally connected therewith near the bottom thereof, the legs being shaped to lie beneath the bottom of the container to hold it above the ground when they are moved into operative position, said legs extending beyond the periphery of the container on the side thereof opposite the side near which they are pivoted, and there shaped to form rockers on which the container may be tilted, and such rocker portions being connected by a cross piece, the whole rocker support being adapted to turn on its pivots into an inoperative position along side the container and above the bottom thereof.

100 Signed at Chicago, county of Cook, and State of Illinois, this 13th day of December, 1927.
